(No Model.)

E. G. TEBBUTT.
PAD HOLDER.

No. 597,035.

Patented Jan. 11, 1898.

UNITED STATES PATENT OFFICE.

ELIZABETH G. TEBBUTT, OF ALBANY, NEW YORK.

PAD-HOLDER.

SPECIFICATION forming part of Letters Patent No. 597,035, dated January 11, 1898.

Application filed February 16, 1897. Serial No. 628,728. (No model.)

To all whom it may concern:

Be it known that I, ELIZABETH G. TEBBUTT, a citizen of the United States, and a resident of Albany, in the county of Albany and State 5 of New York, have invented new and useful Improvements in Saleswoman's Pockets, of which the following is a specification.

My invention relates to improvements in a saleswoman's pocket, in which its front, rear, 10 and end walls may at all times be in condition to give a suitable support to sales-books of different dimensions and allow ready access to such a book, whether longer or shorter; to provide with the front side and end walls 15 elements which may adapt them to be relatively contracted or expanded, as may be advantageous for use with the book to be carried; to so combine with the front wall of the pocket elements which, together with the said 20 wall, may produce a receptacle or receptacles adapted to temporarily receive a saleswoman's instruments required to be used when attendance to a customer is being given; to provide a measuring-tape with a means for suitable support and in readiness for use and 25 with a blank extension which allows the scale portion to be fully carried out from its case for making measurements at different degrees of distances from the saleswoman, and, 30 finally, to provide other elements for effecting other useful results. I attain these objects by means of the elements or devices illustrated in the accompanying drawings, in which—

35 Figure 1 is a view from its front side of a saleswoman's pocket embodying the improvements in this invention. Fig. 2 is a side view of the same. Fig. 3 is a plan view of the side and bottom walls of the same embodying some 40 of the elements in this invention and illustrating the same when opened out flat. Fig. 4 is a plan view of the end walls of the pocket and means for securing them to the front, back, and bottom walls of the same and illustrating a preferred means for securing the 45 same in place. Fig. 5 is a view of the bag from an end thereof with the end wall unconnected. Fig. 6 is a view of the bag having a modified form of construction, and Fig. 7 is 50 a plan view of the same.

The same letters of reference refer to similar parts throughout the several views.

In the drawings, A is a saleswoman's pocket comprising the front side wall A', rear side wall A², bottom B, and lateral or end walls 55 C C. These several walls and bottom of this pocket may be made of any suitable material, as canvas, leather, or other suitable substance or of suitable combinations of such materials as may be selected, and these several walls may have given to them such dimensions of portions thereof and also outlines of form as may be preferred to adapt them for the purposes designed, and they may be wholly or in part integral or be 60 of separate pieces secured together by any preferred suitable known means.

The side walls A' A² embody the upwardly-extended portions a a, which serve as supports to sales-books from their sides when 70 they are of length exceeding, say, five inches, and also the middle recession a' for allowing the fingers and thumb to readily grasp books of short length without being introduced into the pocket, and at the same time the book is 75 wholly below the upper ends of portions a. In some cases I may use but one upwardly-extended portion a, which when employed may be located at the middle of length of the sides A' A² for supporting books of longest 80 length, and in such a case I would provide two recessions, each running down, as recession a', one at each side of the middle extension portion, as indicated by dotted lines in Fig. 3.

The bottom B is preferably made with a 85 length which may adapt the pocket to receive a sales-book of greatest width and with a breadth corresponding to sales-books of greatest thickness, and although this bottom may be made of but a single thickness of material 90 yet the drawings show this bottom to be made with double thickness, as b b', which together form sheath b², adapted to receive the tongue ends C' of end-wall pieces C C when the latter are to be adjustable in character. When 95 bottom B is made with a sheath-like form, its parts are secured to the side walls A' A², preferably by stitchings s s, Fig. 3.

The end-wall pieces C may be made with 100 parallel side edges c c, as shown by full lines in Figs. 2, 4, and 5, or with one edge thereof on an inclined line, as on dotted line c', Fig. 4, or with both edges inclined, as dotted lines c² c², same figure, and although they may be

secured to the side walls A' A² by any suitable known means yet I at present prefer to have them detachably secured thereto and preferably so as to be adjustable at will in relation 5 to said side walls, as might be advantageous when sales-books of varying thickness may be used therewith. Figs. 1 and 2 show lacing-strings D to be my preferred means for securing said end-wall pieces C with the side walls A' A² to render them detachably secured together and adjustable at will as to the distance at which the latter walls may have their upper ends set apart. When lacing-strings D are employed for securing said walls together, 10 suitable holes d d, with or without protecting-eyelets, may be employed for receiving said strings. When the materials of the side walls A' A² are of flexible nature and liable to become bent or out of shape from use, I provide 15 in each upwardly-extended portion a a suitable stiffening element, which I at this time prefer to consist of a strip E of tempered steel (indicated by dotted lines in Fig. 2 and illustrated by full and dotted lines in Fig. 3) of 20 suitable length inserted between the outer material and linings of said walls, and I preferably secure these stiffening-strips in place by means of suitable eyelet-form rivets e. (Shown in the same figures.)

30 Receptacles F, one or more, are provided with the side wall A' and are formed each by a piece, as f, Figs. 1, 2, and 6, so shaped and secured to the material of the side wall A' that it and the material of the latter wall may together 35 constitute a suitable sheath-form pocket for containing instruments, one or more, required to be used by the saleswoman when attending customers, and such pockets or receptacles F so provided will in all cases 40 be exterior to the pocket A and have the material of the same interposed between the book within and the instrument without and allow the inner surface of wall A' to be evenly plane.

45 G G are cords or equivalent suspending-pieces connected below with pocket A and above with a suitable suspension device, as g, which latter may be secured to the dress of the wearer of the pocket, or these cords G 50 may be of such length as to hold from the neck of the wearer of the pocket. A second holding device, as g', preferably in the form of a hook, is shown to be secured to the rear side of wall A², Fig. 2, of the pocket and 55 adapted to engage with a belt worn by the pocket wearer or with a loop or eye secured to the dress.

H is a measuring-tape provided with case H' and adapted to be coiled within the same, 60 preferably by means of a coiling-spring. This tape, its case, and means for coiling the former within the latter are so well known that a particular description of those parts is unnecessary. This tape H has integral with it 65 an extension of material which is blank and constitutes a blank supplement h, operating to so increase the whole length of the tape

material below the measuring-tape portion H that a ready handling of any degree of length of the measuring portion may be had without confusion and with greater convenience for viewing the measure-marks than may be had when the measure-marks are continued down to the case and producing an extension of measuring-scale longer than necessary for making general measurements of customers. The case of this tape H is provided with devices h', one or more, for securing it to the suspension-cord G, and it may be held by said cord at any desired point above the 70 pocket, as may be found to be most convenient for using the tape.

I is a pin-holder, preferably of circular form and of diameter corresponding with that of the case II', to the front side of which this pin-holder is secured, and it is adapted to hold pins i in place and condition for convenient reach and handling of an attendant when required to use the same while attending a customer.

J is a wall-piece, preferably of flexible material and secured to the material of the pin-holder, preferably by stitchings, as s', so as to form with the material of said pin-holder a receptacle j for an instrument required to be in place convenient for easy reach of the wearer when attending on a customer.

By my above-described improvements there are provided with the pocket elements which contribute to the same new and advantageous functions and results and render it adapted for holding articles and instruments conveniently situated for ready use while the saleswoman is attending a customer.

Having described my invention, what I claim, and desire to secure by Letters Patent, is—

1. In a saleswoman's pocket, the combination with a bottom and end walls, of two side walls having each one or more upwardly-extended book-supporting elements a provided with the stiffening-pieces E and provided with downwardly-extended recessions a', whereby a sales-book may be suitably supported and readily grasped, substantially as and for the purposes set forth.

2. In a saleswoman's pocket, the combination with a bottom piece, end pieces or walls, and the front side wall of flexible material, of a stiffening element E applied to said side wall and adapted to prevent said flexible material being bent out of shape, from use, substantially as and for the purposes set forth.

3. In a saleswoman's pocket, the combination with the front and rear side walls, having each one or more upwardly-extended book-supporting elements a and downwardly-extended recessions a', of a stiffening element E applied to the material of each side wall and extending from a point near the bottom of the pocket up to near the upper end of each said book-supporting element, substantially as and for the purposes set forth.

4. In a saleswoman's pocket, the combina-

tion with similar front and rear side walls and bottom, of longitudinally-adjustable end walls C secured each to its adjoining side wall so that the upper end of said pocket may 5 at all times be maintained open substantially as and for the purposes set forth.

5. In a saleswoman's pocket, the combination with the front and rear side walls having in their respective outer end edges a series of 10 lacing-receiving devices, of longitudinally-

adjustable end walls C provided also at their side edges with lacing-receiving devices and lacing-strings applied to said lacing-receiving devices, substantially as and for the purposes set forth.

ELIZABETH G. TEBBUTT.
